UNITED STATES PATENT OFFICE.

MADELEINE VIONNET, OF PARIS, FRANCE.

DESIGN FOR A BOTTLE OR SIMILAR CONTAINER.

Application filed August 20, 1926, Serial No. 18,783, and in France July 27, 1926. Term of patent 14 years.

To all whom it may concern:

Be it known that I, MADELEINE VIONNET, citizen of the French Republic, residing at 50 Avenue Montaigne, Paris, Seine, France, have invented a new, original, and ornamental Design for a Bottle or Similar Container, of which the following is a specification, reference being had to the accompanying drawing, forming part thereof.

I claim:

The ornamental design for a bottle or similar container, substantially as shown.

MADELEINE VIONNET.
